DISPENSING DEVICE

Joseph Schor, San Francisco, and John R. Skoverski, Oakland, Calif.

Application December 17, 1935, Serial No. 54,814

10 Claims. (Cl. 221—60)

Our invention relates to dispensing devices, and particularly to improvements in collapsible tube containers for plastic substances and means for dispensing the contents therefrom.

5 It is among the objects of our invention to provide a container and dispensing means by which plastic substances may be readily dispensed in desired amount with a minimum of waste.

Another object is to provide a dispensing device for tube contained materials which will provide a convenient holder for supporting a tube in upright position; and in which a collapsible tube may be readily mounted and replaced.

Another object is to provide a container and dispensing means for plastic materials such as condiments, by which the material may be effectually preserved from deterioration or contamination by exposure to the air or other outside agencies.

20 Another object of our invention is to provide a collapsible tube container formed of material which is chemically inert, and adapted to insure against reaction with materials contained in the tube.

25 Another object is to provide a dispensing device for tube-contained materials which is attractive in appearance, and which embodies improved features of construction obtaining economy, simplicity, and efficiency in manufacture and use.

The invention possesses other objects and features of advantage, some of which, with the foregoing, will be set forth in the following description of our invention. It is to be understood that 35 we do not limit ourselves to this disclosure of species of our invention, as we may adopt variant embodiments thereof within the scope of the claims.

Referring to the drawings:

40 Figure 1 is a side elevation, partly in vertical section, of a collapsible tube and one form of dispensing holder embodying our invention.

Figure 2 is a transverse sectional view of the holder shown in Figure 1, the section being taken 45 through the key journals.

Figure 3 is a sectional view similar to Figure 2, illustrating a modified structure of the key journals.

Figure 4 is a broken, vertical sectional view 50 of a collapsible container constructed in accordance with our invention.

Figures 5 and 6 are broken vertical sectional views illustrating modified forms of the tube structure.

55 Figure 7 is a side elevation, partly in vertical

section, of a collapsible tube and another form of dispensing holder embodying our invention.

Figure 8 is a broken vertical midsectional view taken upon the line 8—8 of Figure 7 in the direction indicated.

Figure 9 is a sectional plan view of the holder of Figures 7 and 8, the section being taken in the plane of the key.

Figure 10 is a broken side elevation, partly in section, showing a modified means for detachably securing the holder sections together.

In terms of broad inclusion, the dispensing device of our invention comprises a holder arranged to receive a collapsible tube containing a plastic material. The outlet end of the tube extends outwardly from the holder, and is provided with a suitable closure. A rotatable key, or other suitable tube-collapsing means, is mounted upon the base of the holder in engagement with the inner end of the tube; and is arranged to be operated to collapse the tube progressively from its inner end for expressing the contents of the tube through the outlet end thereof. The collapsed portion of the tube is taken up by the key, and is retained within the holder until the contents of the tube have become exhausted.

Our invention also contemplates a collapsible tube having a light, flexible, tubular body portion formed of a regenerated cellulose product, such as "cellophane", which is chemically inert to the substances to be packed in the tube so as to insure against any reaction of the tube with its contents. The tube is preferably provided with an outlet head of relatively rigid structure adapted to maintain its shape and to form a mounting for the tube closure. The head may be formed integrally with the tube; or it may be made separately of the same or different material, and secured to the tube by a seam, or by molding, or by other means adapted to obtain a sealing engagement of the tube with the head.

In terms of greater detail, and referring particularly to the illustrative embodiment disclosed in Figures 1 and 2 of the drawings, the dispensing device of our invention comprises a holder, designated in general by the numeral 1, formed of metal, synthetic resin such as "bakelite", or other suitable material. The holder 1 comprises a hollow base portion open at the bottom, and having a reduced neck portion 2 at the top. The neck portion 2 is arranged to receive a collapsible tube 3 containing a plastic material such as condiments, cosmetics, pastes, ointments, greases, or other similar material of a plastic nature. The tube extends outwardly through the

35

40

45

50

55

neck portion 2 and is provided with an outlet duct 4, having a suitable closure 5, at its outer end.

The inner end of the tube 3 is provided with a flattened end 6 sealed in any suitable manner; and is engaged by a key 7 having a slot 8 arranged to receive the flattened end of the tube. The key 7 extends across the hollow base of the holder 1, and is journaled in openings 9 and 10 formed in opposite sides thereof. The key 7 is provided with a handle 11 extending outwardly from the holder 1 by which the key may be turned to wind the tube onto the key for expressing the contents of the tube through its outlet 4. As the key 7 is rotated in its journals, the flattened end of the tube is wound in a roll onto the key, thereby pressing the contents of the tube toward the outlet end of the tube.

The key 7 may be of any suitable form. For example, the key may be conveniently formed from a strip of metal doubled upon itself to provide a bearing portion 12 at one end, and to form loops comprising the handle 11 at the opposite end. The strands extending from the bearing portion 12 to the handle 11 are spaced sufficiently to form the slot 8 for receiving the end of the tube. The key is insertable through the holder 1 from one side thereof; and is normally held in position upon the holder by its engagement with the inner end of the tube 3. If desired, the key may be stamped or otherwise formed from sheet metal or other suitable material. Instead of a slot 8 closed at both ends, as illustrated in the drawings, the key may be of bifurcated form to provide a slot open at one end so that the key may be moved transversely onto the flattened end of the tube.

The tube 3 is preferably formed of a regenerated cellulose product, such as "cellophane", which is chemically inert and of a character which will insure that no reaction will occur between the tube-forming material and the substance contained therein. The use of such material is particularly desirable in the case of tubes intended for containing condiments such as mustard, mayonnaise, and other paste-like food stuffs containing chemically active ingredients such as vinegar having a tendency to react with metals or other chemically active materials; also for many cosmetics, ointments, and similar medicinal preparations containing chemically active ingredients.

The tube 3 is provided with a head portion 13 of relatively rigid character adapted to maintain its shape, and to form a mounting for the outlet duct 4 and closure 5. The head 13 may be formed integrally with the tube 3, the necessary strength and rigidity being obtained by making the head portion relatively heavy, as illustrated in Figure 4; or the head may be formed separately of the same material as the tube, or of different material as desired. For example, the head 13 may be molded from synthetic resin such as "bakelite." The head may be secured to the end 65 of the tube 3 by molding it onto the edge of the tube as illustrated in Figure 5 of the drawings. Openings 14 may be formed in the edge of the tube 3 through which the molded material may flow to form bonds extending through the tube material to prevent separation of the head from the tube. Indentations, or corrugations may be substituted for the openings 14 as a means for preventing separation of the head from the tube body.

Figure 6 illustrates a structure in which the

head 13 is formed of metal, or other bendable material. In this case, the edge of the head 13 may be joined to the tube 3 by means of a double seam 15.

The closure 5 preferably comprises a cap 5 threaded onto the outlet duct 4. Other means for closing the duct 4 may, of course, be substituted for the threaded cap if desired.

The tube 3 is preferably inserted into the holder 1 through the open bottom thereof, and is advanced to a point such that the key 7 may be inserted. The flattened end 6 of the tube is then inserted into the slot 8 of the key and the key turned sufficiently to grip the end of the tube, and support the tube upon the holder. When it is desired to dispense substance from the tube 3, the closure 5 is removed, and the key 7 is turned sufficiently to press the substance toward the outlet and thereby express the desired amount of substance. As the key 7 is turned, the lower end of the tube is wound onto the key and the tube is progressively collapsed. In this manner, substantially all of the contents may be expressed from the tube. The key 7 may then be turned in the reverse direction to unwind the tube therefrom; and a fresh tube may be inserted in the holder as above explained.

Since the diameter of the roll formed by winding the tube onto the key 7 increases with each turn of the key, there is a tendency for the tube to be tilted out of axial alignment with the holder when several turns of the tube have been wrapped onto the key.

To correct this tendency we prefer to place the journal openings 9 and 10 slightly to one side of the center of the holder 1 as best shown in Figure 2 of the drawings. Such offsetting of the journal openings does not affect the alignment of the tube during the first few turns of the key, and avoids any objectionable tilting of the tube during the subsequent wrapping of the tube around the key. If desired, the journal openings 9 and 10 may be elongated, as best shown in Figure 3 of the drawings, so that the key may be shifted bodily within the journal to maintain the tube in axial alignment with the holder.

The holder 1 is of a size suitable to provide a stable base upon which the tube may be supported in an upright position. The base presents a neat and attractive appearance; and is particularly desirable for table use for dispensing condiments.

Another and perhaps preferable form of the holder is illustrated in Figures 7, 8, 9, and 10 of the drawings. In this form, the holder comprises a base portion 16 and a neck portion 17 detachably engaging the upper end of the base portion. The portion 17 may be held on the base 16 by any suitable securing means. For example, bayonet grooves 18 may be formed in one portion to receive projections 19 correspondingly positioned on the other portion of the holder, as illustrated in Figures 7, 8, and 9. If desired, the portions 16 and 17 may be formed to obtain a press fit for holding the parts together by frictional engagement; or the base portion 16 may be provided with a bead 21 over which the lower edge of the neck portion 17 may be pressed, the bead 21 being received in a groove 22 in the portion 17 for holding the parts together, as illustrated in Figure 10 of the drawings.

In the embodiment illustrated in Figures 7 to 10, the journals for the key 7 are formed by

notches 23 formed in the lower edge of the neck portion 17 matching with notches 24 in the upper edge of the base portion 16. When the base and neck portions of the holder are assembled, 5 the inner ends of the notches 23 and 24 register to form journal openings for the key. The slots may be offset from the center, or they may be widened to form elongated journal openings as above explained in connection with Figures 2 10 and 3.

The separable relation of the base and neck portions of the holder permits the key 7 to be applied to the flat end of the tube before it is inserted into the base 16. The tube, with the 15 key attached, is placed upon the base 16 with the ends of the key resting in the notches 24. The neck portion 17 is then moved into engagement with the base portion 16, with the ends of the key received in the notches 23. In this manner the key and tube are effectually held by the holder; and the contents of the tube may be expressed by turning the key as above explained.

This arrangement obviates the necessity of unwrapping an empty tube from the key before another tube may be inserted in the holder. Since the key is of simple and inexpensive structure, a new key may be supplied for each tube of material without objectionable expense. If 30 desired a key may be fitted and secured to each tube at the time it is packed. In that event, a tube may be inserted into the holder by merely separating the base and neck portions 16 and 17 of the holder and applying them over the 35 tube 3 from opposite ends thereof with the ends of the bearing portions of the key 7 received in the matching notches 23 and 24, as above explained.

The tube effectually protects the contents from 40 deterioration by exposure to the atmosphere. For example, condiments, such as mustard, salad dressings, and similar materials dry out and become discolored when exposed to air. The device of our invention provides a convenient and 45 practicable means for packaging and dispensing such products; and avoids the substantial waste which commonly occurs when they are served in jars or other containers wherein the unused portion of the product is not effectually sealed from 50 exposure to the air after the cover is removed. The tube and dispensing means may be conveniently handled, and of course protects the contents of the tube from contamination by outside agencies.

55 We claim:

1. A dispensing device comprising a holder having a base portion, a neck portion detachably engaging the base portion and having an opening for slidably engaging the body portion of a collapsible tube extending therethrough, and a key 60 journaled upon the holder for engaging the inner end of the tube.

2. A dispensing device comprising a holder having a base portion, a neck portion detachably 65 engaging the base portion and having an opening through which a collapsible tube may extend, registering notches upon the adjacent edges of the base portion and neck portion, and a key journaled in the notches for engaging the inner end of the tube.

3. A dispensing device comprising a holder having a base portion, a neck portion detachably 70 engaging the base portion and having an opening through which a collapsible tube may extend, registering notches upon the adjacent

edges of the base portion and neck portion, a key journaled in the notches for engaging the inner end of the tube, and means for holding the neck portion in engagement with the base portion.

4. A dispensing device comprising a pair of interlocking holder portions forming a base arranged to receive and enclose the sealed end of a collapsible tube and having a reduced neck encircling the tube and through which the body 10 of the tube may extend, journal forming means upon the portions, and a key removably journaled in the journal openings for engaging the inner end of the tube, and being retained in said journal forming means by engagement of 15 the holder portions.

5. A dispensing device comprising a pair of holder portions forming a base arranged to receive and enclose the sealed end of a collapsible tube and having a reduced neck encircling the tube and through which the body of the tube may extend, journal forming means upon one of the portions, a key removably journaled in the journal 20 openings for engaging the inner end of the tube, the key being retained in the journal openings by the other holder portion and means for securing the holder portions in assembled relation over the tube and key.

6. A dispensing device comprising a hollow base having openings in opposite sides thereof and provided with a reduced neck portion upon the top of the base for encircling the filled body portion 30 of a collapsible tube container and movable onto the tube over the outlet end thereof, a key journaled in the openings in the base, the key being slotted to engage the end of the tube within the holder and being rotatable for winding the tube onto the key with the wound portion of the tube 35 enclosed within the base.

7. A dispensing device comprising a hollow base having alined journal openings in opposite sides thereof offset transversely from the axis of the base, a reduced neck upon the top of the base for encircling the filled body portion of a collapsible tube container and movable onto the tube over the outlet end thereof, a slotted key journaled 40 in the openings and engaging the lower end of the tube for winding the same onto the key with the wound portion of the tube enclosed within the base.

8. A dispensing device comprising a hollow base having elongated alined journal openings in opposite sides thereof offset transversely from the axis of the base, a reduced neck portion upon the top of the base for encircling the filled body portion 55 of a collapsible tube container and movable onto the tube over the outlet end thereof, a slotted key journaled in the openings and engaging the lower end of the tube for winding the same onto the key with the wound portion of the tube enclosed within the base, the key being movable within the elongated openings transversely to the body of the base for maintaining axial alinement of the tube and base as the tube is wound onto the key.

9. A dispensing device comprising a holder having a base portion, a neck portion detachably engaging the base portion and having an opening through which the body of a collapsible tube may extend, journal forming notches upon at 60 least one of the portions and having the open ends of the notches closed by the other portion, and a key removably journaled in the notches for engaging the inner end of the tube.

10. A dispensing device comprising a holder 70

having a base portion, a neck portion detachably engaging the base portion and having an opening through which the body of a collapsible tube may extend, journal forming notches upon at least one of the portions and having the open ends of the notches closed by the other portion, and a key removably journaled in the notches for en-

gaging the inner end of the tube, and means upon one holder portion interlocking with means upon the other portion for securing the holder portions in assembled relation over the tube and key.

5
